UNITED STATES PATENT OFFICE.

PHILLIP KRAKAUER, OF NEW YORK, N. Y.

DESIGN FOR A BED-SPRING.

47,336.

Specification for Design.

Patented May 11, 1915.

Application filed October 19, 1914. Serial No. 867,543. Term of patent 7 years.

To all whom it may concern:

Be it known that I, PHILLIP KRAKAUER, a citizen of the United States, and a resident of the city of New York, borough of Brooklyn, in the county of Kings and State of New York, have invented a new, original, and ornamental Design for Bed-Springs, of which the following is a specification, reference being had to the accompanying drawing, forming part thereof.

The figure is a plan view of a bed spring, showing my new design, comprising the peculiar pleasing arrangement of the wire fabric of said spring.

I claim:

The ornamental design for a bed spring, as shown and described.

PHILLIP KRAKAUER.
